E. J. BOYLER.
SEWING MACHINE HEMMER AND THE LIKE.
APPLICATION FILED FEB. 10, 1913.

1,109,898.

Patented Sept. 8, 1914.

UNITED STATES PATENT OFFICE.

EMANUEL J. BOYLER, OF NEW HAVEN, CONNECTICUT, ASSIGNOR TO THE GREIST MANUFACTURING COMPANY, A CORPORATION OF CONNECTICUT.

SEWING-MACHINE HEMMER AND THE LIKE.

1,109,898.

Specification of Letters Patent.

Patented Sept. 8, 1914.

Application filed February 10, 1913. Serial No. 747,389.

To all whom it may concern:

Be it known that I, EMANUEL J. BOYLER, a citizen of Canada, residing at New Haven, in the county of New Haven and State of Connecticut, have invented or discovered certain new and useful Improvements in Sewing-Machine Hemmers and the like, of which the following is a specification, reference being had therein to the accompanying drawings.

This invention has for its object to provide an adjustable hemmer of such construction that the scroll parts thereof may be moved from or toward each other for the purpose of making wider or narrower hems, and which hemmer is adjustably mounted on a presser-foot or support in such a manner that it may be adjusted laterally for the purpose of bringing the seam into any desired relation to the edge of the hem. To this end the improved hemmer comprises a shank portion having what may be termed a fixed scroll part which is preferably formed integral with said shank portion. Movable 25 mounted with reference to the said fixed scroll part of the hemmer is an adjustable member carrying a scroll part the position of which may be changed to vary the width of the hem. The shank of the adjustable hemmer is provided with a slotted portion which receives a stud on a presser-foot adapted to be secured to the presser-bar of a sewing machine; and attached to the said presser-foot is a spring engaging a portion 30 of the shank of the hemmer to maintain the said hemmer in any desired position of adjustment by a frictional engagement with said shank. This construction permits the hemmer to be quickly applied to or removed 40 from the presser-foot part of the attachment, while enabling it to be adjusted laterally, when desired, for the purpose of varying the distance between the line of stitching and the edge of the hem, simply by sliding the said shank to the right or left. This 45 convenient adjustable and removable mounting of the guiding part of the attachment on the presser foot part thereof may be utilized with other sewing machine attachments than hemmers, as with binders, braid- 50 ers and cordiners, etc.

In the accompanying drawing Figure 1 is a plan view of the improved hemmer and its presser-foot support. Fig. 2 is a front view, 55 Fig. 3 a side view and Fig. 4 a rear view of

the same. Fig. 5 is a detail section on line 5—5, Fig. 1.

Referring to the drawing, 12 denotes a presser-foot provided with a shank portion 13 adapted to be secured to the presser-bar of a sewing machine in a well-known manner. Removably mounted on the said presser-foot is a hemmer comprising a shank portion 14 having a slot 15 one end of which is enlarged for the reception of a head of a stud 16 riveted to the presser-foot, and the neck portion of which is closely embraced by the narrow part of the said slot. The said shank portion of the hemmer is provided with an upturned portion or flange 17 fitting against the front of the lower part of the presser-foot shank, and attached to said lower part of the presser-foot shank, by a rivet 18, is a looped spring 19 the free end of which is U-shaped to provide a front portion 20 which overlaps the vertical flange 17 on the hemmer shank and presses against the said flange in such a manner as to frictionally retain the said shank in place, while permitting it to be slid laterally for the purpose of changing the working position of the hemmer, or for the purpose of bringing the head of the stud 16 into register with the enlarged portion of the slot 15 in the shank portion of the hemmer when the latter is to be removed from the presser-foot. The extreme free end of the front portion 20 of the spring 19 is preferably turned outwardly slightly, and the end of the vertical flange 17 is preferably slightly beveled off 90 at 21 to enable the said flange to be conveniently slid into the space beneath the said portion 20 of the said spring.

Preferably formed integral with the shank portion 14 of the hemmer is a fixed scroll 95 part 22 which cooperates with an adjustable scroll part 23 carried by a looped member 24 the upper limb of which is provided with a slot 25 receiving a rib 26 mounted on the shank portion of the hemmer, so that the 100 said looped member 24 will be guided by the said rib when adjusted laterally and will be steadied thereby when secured in any desired position of adjustment by means of the set screw 27 tapped in said rib. Beneath 105 the base of the head of the said screw 27 is preferably placed a washer 28 which overlies portions of the upper limb of the said adjustable loop member and bears directly thereon.

From the foregoing it will be understood that the hemmer may be made wider and narrower by moving the adjustable scroll part 23 thereof toward or from the fixed scroll part 22 thereof, for the purpose of forming narrower or wider hems, as may be desired. It will also be understood that by adjusting the shank portion of the hemmer laterally on the presser-foot the line of stitching may be varied with reference to the edge of the hem, as may be desired.

By reference to Figs. 1 and 2 of the drawing it will be seen that the fixed scroll part 22 of the hemmer is inclosed between the upper and lower limbs of the looped member 24 with which the adjustable scroll part 23 of the hemmer is integral. When the hemmer is in working position on a sewing machine the lower limb of said looped member 24 is slightly above the work-plate of the machine, while the adjustable scroll part 23, forming the lower hemmer member, may rest on the work-plate. Owing to this arrangement of the hemmer parts the forward feed or travel of the cloth, in forming a hem, will not be impeded by a downward pressure thereon by the hemmer, as the cloth will pass above the lower portion of the adjustable scroll part 23, and thus such dragging pressure on the cloth beneath the hemmer as would have a tendency to distort the roll or fold which is to form the hem will be avoided.

The construction above described provides convenient means whereby a hemmer or other similar attachment may be readily and quickly applied to or removed from its supporting presser-foot, or may be adjusted laterally thereon, without requiring the tightening or loosening of a set-screw or similar device, the attachment being retained in any desired position of adjustment on the

presser-foot by means of the frictional hold of the portion 20 of the spring 19 against the upturned flange on the shank portion of the attachment.

Having thus described my invention I claim and desire to secure by Letters Patent:

1. The combination with a sewing machine presser-foot, of a hemmer adjustably mounted on said foot so that its working position on said foot may be varied laterally, said hemmer comprising fixed and adjustable scroll parts, a looped member on which said adjustable scroll part is formed, said fixed scroll member being located in a plane between the upper and lower limbs of said looped member; whereby hems of different widths may be formed, and whereby also a dragging pressure, beneath the hemmer, on the roll or fold of cloth which is to form the hem, will be avoided.

2. A sewing machine attachment comprising a presser-foot provided with a headed stud, an attachment part having a shank provided with a slot having an enlarged portion to permit the head of said stud to pass through said shank, the said shank having an up-turned flange fitting against the shank portion of said presser-foot, and a looped spring attached to the said shank portion of said presser-foot and having a spring member which overlaps and bears against the said up-turned flange to hold the attachment part in place frictionally, but permitting it to be readily adjusted or removed.

In testimony whereof I affix my signature, in presence of two witnesses.

EMANUEL J. BOYLER.

Witnesses:

HERBERT B. DARTON,
W. GREIST.
